POPCORN VENDING MACHINE

James O. Coltman, Pleasant Ridge, Mich., assignor, by mesne assignments, to Louis K. Obdyke, Glendale, Calif.

Application May 18, 1938, Serial No. 208,667

19 Claims. (Cl. 53—4)

This invention relates generally to coin controlled dispensing apparatus and refers more particularly to popcorn vending machines.

It is one of the principal objects of the present invention to provide popcorn dispensing apparatus embodying relatively simple means for effectively popping the raw corn, salting the popcorn subsequent to the popping operation, and dispensing the same. In accordance with 5 the present invention, the apparatus is responsive to the operation of the usual coin controlled device for automatically discharging a measured quantity of raw corn into the popper, agitating the corn during the popping operation, effectively salting the popcorn in timed relation to completion of the popping operation, and dispensing the popcorn in a package previously located by the operator in a convenient position.

Another advantageous feature of the present 20 invention resides in the novel relatively simple inexpensive mechanism provided for effecting the above operations in the proper sequence and in the minimum length of time.

Still another object of the present invention 25 consists in the salter and in the novel means in which the salter is operated in timed relation to the completion of the popping operation to effectively distribute the salt over the popcorn.

A further feature of this invention resides in 30 the novel mechanism employed for automatically starting a cycle of operation of the mechanism and for automatically stopping this mechanism at the end of the cycle.

A still further advantageous feature of the 35 present invention resides in the novel manner in which the proper quantity of raw corn is discharged into the popper and in the relatively simple means for effecting automatic operation of this mechanism.

40 In addition to the foregoing, the present invention contemplates arranging the driving mechanism and a substantial number of the parts involved on a common support secured to the casing of the apparatus by mountings characterized in that they absorb vibrations and prevent the latter from being transmitted to the outer casing.

The foregoing, as well as other objects, will be 45 made more apparent as this description proceeds, especially when considered in connection with the accompanying drawings, wherein:

Figure 1 is a front elevational view of a coin controlled popcorn vending device constructed in accordance with this invention;

55 Figure 2 is a view similar to Figure 1 having

parts of the casing broken away for the sake of clearness;

Figure 3 is a plan view having certain parts of the construction removed for the sake of clearness;

Figure 4 is a fragmentary side elevational view showing the relationship of the two operating cams;

Figure 5 is a sectional view taken substantially on the plane indicated by the line 5—5 of 10 Figure 3;

Figure 6 is a sectional view taken substantially on the plane indicated by the line 6—6 of Figure 2;

Figure 7 is a sectional view taken substantially on the plane indicated by the line 7—7 of 15 Figure 6;

Figure 8 is a sectional view taken substantially on the plane indicated by the line 8—8 of 20 Figure 3;

Figure 9 is a sectional view taken substantially on the plane indicated by the line 9—9 of Figure 2;

Figure 10 is a side elevational view of the construction shown in Figure 9 illustrating the parts 25 in different positions;

Figure 11 is a fragmentary side elevational view of the coin controlled mechanism;

Figures 12 and 13 are respectively fragmentary side elevational views of a part of Figure 11 30 showing the parts in different positions;

Figure 14 is a detailed sectional view taken substantially on the plane indicated by the line 14—14 of Figure 13;

Figure 15 is a fragmentary side elevational 35 view of the popcorn salting device;

Figure 16 is a sectional view taken substantially on the plane indicated by the line 16—16 of Figure 15; and

Figure 17 is a view similar to Figure 8 showing 40 the popper in its discharge position.

In general, the coin actuated popcorn vending machine selected for the purpose of illustrating the present invention embodies a conventional coin controlled mechanism 20 having the 45 usual reciprocable operating bar 21 normally urged to its outermost position shown in Figure 11 by means of the spring 22. In accordance with conventional practice, the mechanism 20 is provided with means (not shown) for locking the 50 operating bar 21 in its outermost position, and this means is releasable by inserting a coin 23 in the slot provided therefor.

After a coin 23 has been inserted in the coin slot of the mechanism 20, the bar 21 may be 55

5 moved inwardly by the operator against the action of the spring 22. As the bar 21 is moved inwardly, the coin 23 is deposited in a gravity operated chute 24 and is ultimately dropped into
 10 a coin receiving receptacle 25 shown in Figure 2 of the drawings. In addition, inward movement of the bar 21 from the position thereof shown in Figure 11 operates a switch 26, shown in Figure 14, to close a circuit to the electric motor
 15 27. As will be apparent from the following description, the electric motor 27 is operatively connected to the several instrumentalities of the apparatus and functions to operate these instrumentalities in predetermined timed relationship
 20 to perform one complete cycle of operation. During one complete cycle of operation, the following functions are performed in their proper sequence: 1. The proper quantity of raw corn is discharged from a hopper 28 into a popper 29
 25 where it is thoroughly popped in the presence of the desired oil; 2. After a predetermined interval of operation of the popper 29, the popcorn is discharged from the latter; 3. The popcorn is salted by a salter 30 before it is dispensed by the operator into a bag 31 which has previously been positioned in a recess 32 conveniently located in one side of a casing 33 for the apparatus; and 4. The switch 26 is automatically operated to open the circuit to the electric motor 27 to thereby
 30 discontinue the operations of the instrumentalities provided for accomplishing the foregoing results.

Switch operating mechanism

35 Referring more in detail to the switch operating means, it will be noted from Figures 11 to 14, inclusive, that a trip 34 is secured to the inner end of the operating bar 21 for movement with the latter as a unit. The trip 34 is in the 40 form of an L-shaped strip having the short leg secured to the inner end of the bar 21 and having the longer leg fashioned to form a cam 35 engageable with a dog 36 to swing the latter upwardly about its pivotal connection 37 with a 45 supporting plate 38. In Figure 11 of the drawings, the free end of the dog 36 is shown as engageable in a notch 39 formed in the periphery of a ratchet wheel 40 and movement of the dog 36 upwardly about the pivot 37 releases the free 50 end of the dog from the first notch 39. As a result, the ratchet wheel 40 is free to rotate about its pivotal connection 44 with the plate 38 and this rotative movement is effected in the direction of the arrow 42 by a spring 41. In 55 this connection, it may be pointed out that the upper end of the spring 41 is attached to a lug 43 extending laterally from the dog adjacent the free end thereof, and the lower end of the spring is connected to the ratchet wheel 40 adjacent the periphery of the latter. It may also be pointed 60 out at this time that the lug 43 provides an abutment for engagement with the cam portion 35 of the trip 34 to lift the free end of the dog from the ratchet wheel 40 when the operating bar 21 is moved from the position shown in Figure 11 to the position shown in Figure 12.

65 It will, of course, be understood from the above construction that lifting of the free end of the dog 36 from the ratchet wheel 40 tensions the spring 41 and effects rotation of the ratchet wheel 40 about its pivotal connection 44 with the plate 38. The extent of rotation of the ratchet wheel 40 in the direction of the arrow 42 is definitely determined by an arm 45 depending from the 70 dog 36 and engageable in a notch 46 formed in
 75

the periphery of the ratchet wheel 40. The arrangement is such that when the dog 36 is swung by the operating bar 21 from the position shown in Figure 11 to the position illustrated in Figure 12, the free end of the arm 45 is moved in a 5 direction toward the periphery of the ratchet wheel 40 so as to be in a position to engage in the notch 46 and to stop rotation of the ratchet wheel by the spring 41.

Upon completion of the above operation, the 10 operating bar 21 is returned to its outermost position by the spring 22 and, since the trip 34 is secured to the arm, it follows that this trip is moved to its initial starting position wherein the cam portion 35 of the trip is free from engagement with the dog 36. As a result, the free end of the dog is returned toward the periphery of the ratchet wheel and the free end of the arm 45 is released from the notch 46 in the ratchet wheel. As soon as the arm 45 is released from 20 the notch 46, the ratchet wheel 40 continues to rotate in the direction indicated by the arrow 42 under the action of the spring 41 until the dog abuts a shoulder 47 on the ratchet wheel 40 provided by a second notch 48 in the periphery of 25 the ratchet wheel.

With the above in mind, reference will now be made to Figure 14 wherein it will be noted that the switch 26 is mounted on the side of the supporting plate 38 opposite the ratchet wheel 40 30 and comprises a stationary contact 49 arranged in one side of the electric circuit to the motor 27 and a movable contact 50 located in the other side of the circuit to the electric motor. The movable contact is carried by the free end of an 35 arm 51 pivoted intermediate the ends thereof, as at 52, and normally urged to effect engagement of the movable contact with the fixed contact by means of a spring 52'. The spring 52' is normally prevented from closing the contacts 40 by means of a follower 53 slidably mounted in the switch casing 54 and having the free end extending through an opening 55 in the plate 38 to a position adjacent the ratchet wheel 40. As 45 a matter of fact, the free end of the follower 53 is frictionally urged into engagement with the adjacent side of the ratchet wheel 40 by means of the spring 52' and the length of this follower is such that the movable switch contact 50 is maintained in spaced relationship to the fixed 50 contact 49 so that the circuit to the electric motor 27 is normally open. However, the ratchet wheel 40 is provided with a laterally outwardly struck-out portion 56 providing a recess 57 of sufficient 55 depth to receive the free end of the follower 53 and permit the spring 52' to close the switch. The recess 57 is predeterminedly positioned on the ratchet wheel 40 so as to register with the free end of the follower 53 during the interval the ratchet wheel 40 moves from the position thereof 60 shown in Figure 12 to the position shown in Figure 13. In other words, when the coin controlled operating bar 21 is returned to its outermost position, the circuit to the electric motor 27 is automatically closed by the switch 26. As will be 65 more fully hereinafter set forth, the electric motor 27 drives a shaft 58 at a very reduced speed in a counterclockwise direction indicated in both of Figures 3 and 11 by the reference character 59. In the present instance, the shaft 58 makes 70 one complete revolution during the cycle of operation of the apparatus briefly referred to above. One of the several functions of the shaft 58 is to open the switch 26 to the prime mover 27 upon completion of the dispensing operation and, for 75

this purpose, a cam 60 is secured to one end of the shaft 58. The cam 60 assumes the position thereof shown in Figure 11 when the cycle of operation is initially started and, upon completion 5 of the cycle of operation, operates a link 61 to return the ratchet wheel 40 to its initial starting position illustrated in Figure 11. Of course, movement of the ratchet wheel 40 in a direction opposite to the direction indicated by the arrow 10 42 effects the movement of the recess 57 relative to the follower 53 required to open the switch 26. In this connection, it will be noted from Figure 14 that the wall 62 of the recess 57 is inclined so as to have a cam action on the free end of the 15 follower 53 to return the latter into engagement with the adjacent plane surface of the ratchet wheel.

Referring now more in detail to the switch opening means, it will be noted that the link 61 is provided with an elongated slot 63 in the upper end thereof adapted to slidably receive a fastener element 64 secured to the frame 65, and the lower end of the link is guided in a slot 66 formed in a flange 67 bent laterally from the bottom edge 20 of the plate 38. The link 61 is also formed with a shoulder 67', adjacent the upper end thereof, adapted to be engaged by a lug 68 extending radially from the cam 60 when the shaft 58 approaches the end of one complete revolution from 25 the position thereof shown in Figure 11. It follows from the above that as the shaft 58 is moved throughout the end portion of its travel, the lug 68 engages the shoulder 67' and moves the link 61 downwardly against the action of a spring 70 having one end connected to the link 61 and having the opposite end secured to the fastener element 64. It will also be observed from Figure 30 11 that a shoulder 71 is formed on the link adjacent the lower end thereof, and this shoulder 35 is adapted to abut a radial shoulder 72 formed on the periphery of the ratchet wheel 40. The location of the shoulder 71 is such that when the link 61 is moved downwardly, this shoulder assumes a position at the underside of the shoulder 72 on the ratchet wheel 40 and in order to 40 insure registration of the shoulder 71 with the shoulder 72, a spring 73 is provided for normally urging the lower end portion of the link 61 toward the ratchet wheel 40. As shown in Figures 45 50 11 to 13, inclusive, one end of the spring 73 is connected to the lower end of the link 61 and the other end of the spring is connected to the plate 38.

After the link 61 has been moved downwardly 55 by the cam and the lower end of the link is moved toward the ratchet wheel 40 to locate the shoulder 71 below the shoulder 72, the cam projection 68 releases the link 61. As a consequence, the spring 70 returns the link 61 to its uppermost position, shown in Figure 11 and, during this movement, rocks the ratchet wheel 40 back to its position 60 shown in Figure 11. This return movement of the ratchet wheel 40 is against the action of the spring 41 operating on the dog 36, with the result 65 that this spring is tensioned and serves to insure engagement of the end of the dog in the first notch 39 formed in the periphery of the ratchet wheel. It will, of course, be understood from Figure 14 that rocking movement of the ratchet wheel 40 in a direction opposite the direction 42 permits the follower 53 to open the switch 26.

It has previously been stated that the shaft 58 is rotated one complete revolution by the motor 27 during one cycle of operation of the apparatus. 70 Upon reference to Figure 3, it will be noted that

the drive shaft 75 of the motor has a worm 76 secured thereto, and this worm meshes with a worm wheel 77 fixed to a shaft 78 for driving the latter at a reduced speed. The shaft 78 is operatively connected to a countershaft 79 through the 5 medium of reduction gearing 80 for rotating the countershaft and the latter has a worm 81 secured thereto for intermeshing engagement with a worm wheel 82 fixed to a shaft 83. The shaft 83, in turn, has a worm 84 secured thereto, and this worm is adapted to mesh with a worm wheel 85 secured to the shaft 58. It follows from the above that a substantial reduction is provided between the drive shaft 75 of the motor and the shaft 78. The ratio of the reduction is predetermined so that the shaft 58 makes one complete revolution during the interval the apparatus 10 operates through one complete cycle. 15

Hopper unit construction

Reference has been made above to the fact that raw corn is discharged from the hopper 28 to the corn popper 29 and the following construction is provided to insure delivering the proper quantity of raw corn to the popper 29. Upon 20 reference to Figures 2, 9 and 10, it will be noted that the discharge end of the hopper 28 communicates with a downwardly extending delivery conduit 86 having a chute 87 for guiding the raw corn into the popper 29. Located within the 25 delivery conduit 86 between the discharge end of the hopper 28 and the upper end of the chute 87 is a transfer valve 88 comprising a cylinder 89 secured to a revolvable shaft 90 and having a recess 91 of predetermined capacity therein. The cylinder 89 is rotated by the shaft 58 from a position wherein the recess 91 registers with the outlet opening 92 in the lower end of the hopper 28 to the position shown in Figure 10 wherein the raw corn in the recess 91 falls by gravity onto 30 the chute 87. As will be presently set forth, the cylinder 89 is driven from the shaft 58 so as to make one complete revolution during the cycle 35 of operation of the apparatus. The cylinder 89 assumes the position shown in Figure 9 at the 40 start of rotation of the shaft 58, with the result that all of the corn collected in the recess 91 is discharged onto the chute 87 during the 45 interval the cylinder passes through one complete revolution from the position thereof shown 50 in Figure 9.

The outlet opening 92 at the lower end of the hopper 28 is restricted by means of a shutter 93 and a guard 94. The shutter 93 restricts the width of the opening 92, while the guard 94 is 55 constructed to restrict the length of the opening 92 to the approximate length of the recess 91 in the cylinder 89. As a result, all of the raw 60 kernels passing through the outlet opening 92 are compelled to flow into the recess 91. As a further 65 precaution of preventing escape of raw kernels from the hopper 28, the free end of the shutter 93 is provided with a depending flange 95 which extends to a point in close proximity to the periphery of the cylinder 89 and cooperates with the solid portion of the cylinder to prevent the escape of kernels therebetween. It will also be observed from Figure 10 that the rear wall 96 of the guard is bent to extend to a point in close proximity to the periphery of the 70 cylinder 89 so that kernels are prevented from falling directly from the hopper 28 to the chute 87. In addition, the raw kernels deposited in the recess 91 in the cylinder 89 are prevented from falling directly onto the chute 87 by means 75

of a guard 97 secured to the front wall of the delivery conduit 86 and having a portion extending in close proximity to the periphery of the cylinder. This portion is formed on a radius 5 having its radii on the axis of rotation of the cylinder and is of such length as to retain the raw kernels in the recess 94 until the cylinder 89 has rotated to such an extent that the solid portion thereof closes the outlet opening 92 in the 10 bottom of the hopper.

The valve 88 is operated by a cam 98 secured to the shaft 58 and having a cam groove 99 engaged by a follower 100, shown in Figure 3 as connected to a rock arm 101 intermediate the 15 ends of the latter. The inner end 102 of the rock arm is rotatably supported on the shaft 103 and the outer end of the arm 101 is pivotally connected to the upper end of the link 104, shown in Figure 2 of the drawings. The lower end of the link 104 is pivoted to the outer end of the link 105 which is fulcrumed intermediate the 20 ends thereof at the point 106 and has the inner end pivotally connected to a connecting rod 107. The connecting rod 107 is fixedly secured to the lower end of a link 108, shown in Figure 10 as 25 operatively connected to a crank arm 109 which is secured to one end of the shaft 96.

The cam 98 is shown in Figure 4 in its initial starting position and, as it rotates in the direction of the arrow 59, a portion of the cam surface 110 operates the crank arm 109 through the linkage previously described to rock the cylinder 89 in the direction of the arrow 111 in Figure 9 to deposit a predetermined quantity of 30 raw corn into the popper 29.

At the same time that the valve 88 is operated by the cam 98, suction is placed on the tube 112 to insure maintaining the proper level of the selected popping oil in the vat 113 within 35 which the popper 29 is supported. Upon reference to Figure 2, it will be noted that the upper end of the tube 112 extends into the vat 113 and terminates at a point above the bottom of the vat predetermined in dependence upon the level of the oil desired. The opposite end of the tube 112 communicates with the discharge side of a suitable oil pump 114 which is supported within an oil supply tank 115. The pump 114 includes a piston 116 operating in a cylinder 117 and connected to the lower end of the connecting rod 107. Inasmuch as the link 105 is fulcrumed intermediate the ends thereof at 106 and in view of the fact that the outer end of this link is moved downwardly by the cam 98, it follows that the upper end of the connecting rod 107 is moved upwardly. This effects a corresponding upward movement of the piston 116 and, as a result, any excess oil in the vat 113, above the level of the lower end of the tube 112, is drawn back into the cylinder 117 below the piston. 40

Popper unit 29

The popper unit 29 includes a container 120 having a perforated bottom wall 121 and communicating at the top thereof with the lower end 45 of the chute 87 through the medium of the conduit 122. The container 120 is supported in the vat 113 with the perforated bottom wall 121 slightly below the level of the oil indicated in Figure 8 by the reference character 123. The 50 oil is heated by an electrical unit 124 and is maintained at the proper temperature by a thermostat 125 suitably supported on the bottom of the vat 113.

The container 120 is oscillated in the vat 113 55 to effect the popping operation by means of a

cam 126 driven by the shaft 79. The cam 126 is secured to the shaft 79 at a point intermediate opposite side walls of the container 120 and directly engages an operating strap 127 adjacent the upper end thereof. The lower end of the 60 operating strap is secured to the frame 65 by a fastener element 128 and is normally yieldably urged into abutting engagement with the cam 126 by means of a leaf spring 129. The upper end of the strap is provided with an inwardly 65 projecting portion 130 engageable with a wear plate 131 secured to the adjacent side of the container 120.

The container 120 is yieldably urged in a direction to effect engagement of the wear plate 131 70 with the inner end of the projection 130 on the strap 127 by means of a leaf spring 132 having the lower end secured to the opposite side of the container 120 and having a bowed intermediate portion 133 abutting the radius 134 formed at 75 the upper end of the adjacent wall 135 of the vat 113. The construction is such that rotation of the cam 126 by the shaft 79 reciprocates the container 120 and agitates the corn in the container during the popping operation. 80

The container 120 is supported for reciprocation in the vat 113 on a pair of rods 136 shown in Figure 3 of the drawings as extending along opposite sides of the container in the direction of reciprocation of the latter. The adjacent side 85 walls of the container are provided with laterally outwardly extending flanges 137 bent at the outer edges thereof to form tubes 138 of sufficient diameter to slidably receive the rods 136. The rods 136 are bent downwardly at their inner ends 90 in the manner shown in Figure 8 and are secured to a rockshaft 139. The arrangement is such as to permit the container 120 to be swung upwardly about the axis of the shaft 139 after the popping operation is completed. In this connection, it will be noted that the wall 140 of the container, on which the leaf spring 132 is secured, is in the form of a door pivoted at its lower edge for outward swinging movement and thereby permitting the popcorn to be discharged 95 from the container.

Upon reference to Figure 17, it will be noted that when the container is swung upwardly about the axis of the shaft 139, the radius 134, at the upper end of the wall 135 of the vat, engages the 100 wall 140 of the container along the bottom pivoted edge of this wall. As a result, the wall 140 is free to swing open under the action of gravity and the popcorn falls on a pivoted platform 141. 105

Operating mechanism for swinging popper container to a discharge position

The shaft 139 is rocked to swing the popper container 120 to the position shown in Figure 17 by means of a cam 142 secured to the 110 shaft 58 and having a cam groove 143 within which a suitable follower 144 is located. The follower 144 is secured to the free end of a rock arm 145 having the opposite end secured to the rockshaft 103 for movement as a unit with the 115 latter. The cam 142 is in the position shown in Figures 4 and 5 at the start of a cycle of operation so that during initial rotation of the cam 142, the follower 144 travels along the concentric portion 146 of the cam groove. In 120 other words, the cam 142 is inoperative during the interval the cam 98 operates to perform the above functions and also during the interval required for popping the raw corn. However, as soon as the raw corn is popped, the follower 125 125

144 is compelled to travel along the portion 148 of the cam groove and, during this interval, the shaft 103 is rocked by the follower arm 145.

5 The outer end of the rockshaft 103 is operatively connected through the medium of linkage 149 to the outer end of the shaft 139, and this shaft is rocked in the direction of the arrow 150, shown in Figure 8 of the drawings. Inasmuch as the rods 136 are secured to the shaft 139, it necessarily follows that these rods are swung upwardly about the axis of the shaft 139, with the result that the popcorn container 120 is located in the position thereof shown in Figure 17 wherein the popcorn is discharged onto the platform 141.

15 *Salter*

When the popcorn is deposited on the platform 141, the same is automatically salted by the salter 30. In the present instance, the salter comprises 20 a receptacle 152 adapted to contain a quantity of salt and having a downwardly inclined bottom wall 153. Upon reference to Figure 15, it will be noted that the side of the receptacle, adjacent the lower end of the bottom wall 153, is apertured 25 as at 154 to permit the salt to be discharged from the receptacle. This aperture is normally closed by means of a plate 155 pivoted to the adjacent side wall of the receptacle in overlapping relationship in the discharge opening 154. Sealed to the upper edge of the plate 155 is a suitable cup 156 effective upon swinging the plate 155 downwardly to communicate with the interior of the receptacle 152 through the discharge opening 154.

30 The plate 155 is swung downwardly about its pivotal connection with the receptacle by means of a cam 157 secured to the shaft 139 and having a projection 158 engageable in a notch 159 formed in a reciprocable bar 160. The bar 160 is slidably supported upon a plate 161 and is normally urged 35 in a direction against the action of the cam 157 by means of a spring 162. Upon reference to Figure 15, it will be noted that one end of the spring 162 is secured to the plate 161 and the other 40 end of the spring is secured to the bar 160. As a result, when the cam 157 is rotated in the direction 45 163, the projection 158 engages in the notch 159 of the bar and moves the latter in a direction against the action of the spring 162 until the 50 projection releases the arm, at which time the spring quickly returns the bar to its initial position.

The bar 160 is shown in Figures 15 and 16 as operatively connected to the plate 155 in a manner such that movement of the bar by the cam lowers the plate 155 to a position wherein the cup 156 registers with the discharge opening 154, and movement of the arm in the opposite direction by the spring quickly returns the plate 155 55 to the position thereof shown in Figure 16. Of course, as the plate returns to this latter position, the salt in the cup is thrown out and is scattered over the popcorn supported on the platform 141 directly below the salter. The operative connection between the bar 160 and the plate 155 comprises a bell crank lever 165 pivoted intermediate its ends, as at 166, on the plate 161. The arm 167 of the bell crank has a slot and pin connection with the bar 160, while the other arm 60 is pivotally connected to the lower end of a link 168 having the upper end adjustably secured to the plate 155 at a point spaced from its pivotal connection to the receptacle. Attention may also be called to the fact at this time that the plate 155 is slotted, as at 169, to receive a pin 170

projecting from the adjacent wall of the receptacle. The length of the slot is predetermined to provide the required swinging movement of the plate to empty the cup of salt and serves as a stop to limit the extent of movement of the bar 160 by the spring 162.

5 In order to insure discharging the salt from the cup 156 after the popcorn is deposited on the platform 141, it will be noted from Figure 15 that when the cam 142 operates to swing the popcorn container 120 upwardly, the cam 157, of course, rotates in a direction opposite to the direction of the arrow 163 to locate the projection 158 in registration with the notch 159. As stated above, this operation takes place during the interval the cam follower 144 is moving along the portion 148 of the cam groove 143 and when this follower 144 travels along the portion 148' of the cam groove 143 to rotate the shaft 139 in the direction of the arrow 163 to return the popcorn 20 container into the vat, the projection 158 engages in the notch 159 to effect operation of the salter. In other words, the salter is not operated until after the popcorn has been deposited on the platform 141 and the popping container 120 is on 25 its way back to its initial starting position in the vat 113.

Upon completion of the above operations, the platform 141 may be swung downwardly by manipulation of the control 171 projecting 30 through the casing 33 of the machine. Downward movement of the platform 141 discharges the popcorn on the platform into a funnel 173 which has the lower end thereof communicating with a bag 31 supported in the recess 32 in the casing 33. It may be pointed out at this time that provision is made to separate any unpopped kernels from the popcorn before the platform 141 is operated to discharge the popcorn into the funnel 173. Upon reference to Figure 17, it will 35 be noted that a grating 175 is arranged beyond the lower edge of the upwardly inclined platform 141, and this grating is shown in Figure 3 as comprising a plurality of spaced bars 176 secured at one of their ends to the lower edge of the platform 141. The platform 141 is inclined in a direction to assist the unpopped kernels in finding their way to the grating 175, and the spacing of the bars 176 is such as to permit the kernels to 40 drop into a removable receptacle 177.

45 As the follower 144, associated with the cam 142, travels along the portions 148 and 148' of the cam groove 143 to operate the popping container 120 and the salter, the follower 100, associated with the cam 98, travels along the portion 179 of the cam groove 99. As the follower 100 travels 50 along the portion 179 of the cam 98, it operates to return the cylinder 89 to its initial starting position shown in Figure 9 and to also force the oil pump piston 116 downwardly in the cylinder 117. As a result, oil is discharged into the vat 60 113 through the conduit 112 to replenish the supply.

55 In accordance with the present invention, the popper unit 29, motor 27, the drive shaft 58, and the intermediate shafts including the reduction gearing operatively connecting the motor 27 to the drive shaft 58, are all mounted on a common support 180. As a result, the above parts form a sub-assembly capable of being installed and removed as a unit from the apparatus. Upon reference to Figure 6, it will be noted that the support 180 comprises a platform 181 and a pair of side rails 182 extending beyond the inner end of the platform to provide a support for the plate 70 75

161 and the supporting brackets 183 for the shaft 139, shown in Figure 15. The platform 181 is secured to the rails 182 and the latter, in turn, are secured to the casing 33 of the apparatus through the medium of rubber bushings, designated in Figure 7 by the reference character 184. The rubber bushings serve to dampen the vibration of the operating mechanism and insulate the mechanism from metallic contact with the casing 33 of the apparatus.

Upon reference to Figure 8, it will be noted that the vat 113 is enclosed in a casing 185 and the bottom wall of the vat is spaced above the adjacent wall of the casing 185 a sufficient distance to accommodate the heating element 124. In the present instance, the casing 185 is provided with an extension 186, shown in Figures 2 and 15 as surrounding the platform 141 beneath the salter 30. In other words, the side walls of the extension 186 cooperate with the platform 141 to form a container for the popcorn discharged from the popper container 120. It will also be observed from the above figures that the funnel 173 and support 187 for the waste container 177 are formed integral with the extension 186. As a matter of fact, the construction is such that the casing 185 and extension 186 may be formed by a stamping operation, and this is desirable in that it offers the possibility of not only minimizing the number of parts, but reducing the cost of manufacture as well.

Operation

The operator places a coin 23 in the slot provided therefor in the mechanism 20 and pushes the operating bar 21 inwardly against the action of the spring 22. As previously stated, movement of the operating bar 21 inwardly from the position thereof shown in Figure 11 to the position designated in Figure 12 operates the switch 26 in Figure 14 to close the circuit to the electric motor 27 shown in Figure 3. Through several sets of reduction gearing, the electric motor 27 rotates the cams 98 and 162 one complete revolution from the positions thereof shown in Figure 4. While the cams are identical in construction, nevertheless, they are out of phase with one another so that the cam 98 operates initially to rotate the valve cylinder 89 in Figure 9 to discharge the proper amount of raw kernels into the popper container 120 shown in Figure 8. At the same time, the cam 162 is rotated to reciprocate the popper container 120 during the interval the raw corn is popped by the heated oil in the bottom of the vat 113.

At the termination of the popping operation, the cam 162 operates to move the popping container to the position thereof shown in Figure 17, at which time the door 140 opens and the popcorn is discharged onto the platform 141. Upon reference to Figure 15, it will be noted that during the operation of the cam 162 to tilt the popper container 120 to the position shown in Figure 17, the cam 157 is rocked in a direction opposite the direction of the arrow 163 to locate the projection 158 on the cam in registration with the notch 159 on the reciprocable bar 160. The cam 98 then performs its second phase of operation by returning the cylinder 89 of the valve 88 to its initial starting position shown in Figure 9 and also operates the pump 114 shown in Figure 2 to replenish the supply of oil in the vat 113. The cam 142, on the other hand, performs its second phase of operation which includes returning the popper container 120 to its initial position in the vat 113 and rotates the cam 157 in Figure 15 in

the direction of the arrow 163 to move the cup 156 on the salter in registration with the discharge opening 154. As stated above, movement of the bar 160 in a direction to effect the above operation tensions the spring 162 and, as soon as the projection 158 on the cam 157 releases from the notch 159, the bar is quickly returned to the position thereof shown in Figure 15 and the salt in the cup 156 is distributed over the popcorn on the platform 141. This is accomplished as the cam 142 returns to its position shown in Figure 4 and, during this interval, the cam 98 moves the piston 116 in the pump cylinder 117 upwardly to draw any excess oil in the vat back into the supply chamber 150. During the above series of operations, the cam 60 on the shaft 58 moves the link 61 in Figure 11 downwardly and operates the switch 26 to open the circuit to the electric motor 27.

What I claim as my invention is:

1. In popcorn dispensing apparatus, a cup adapted to contain a quantity of a granular substance and movable from an upright position to a discharge position, means for moving the cup from the upright position to the discharge position at a relatively fast rate, and a positive stop arranged to arrest movement of the cup in the discharge position thereof and effective to cause a discharge of the granular substance from the cup in the form of a spray. 20

2. In popcorn dispensing apparatus, a receptacle adapted to contain a granular substance and having a discharge opening in one side wall through which the substance is adapted to flow, a cup located to receive a quantity of the granular substance flowing through said discharge opening, and means for actuating the cup to distribute the granular substance therein over the popcorn. 30

3. In popcorn dispensing apparatus, a platform adapted to support the popcorn, a receptacle adapted to contain a granular substance and having a discharge opening in one side wall through which the granular substance is adapted to flow, a pivotally supported cup located to receive a quantity of the granular substance flowing through said discharge opening and movable from the latter position to a discharge position, means for moving said cup at a relatively fast rate to the discharge position thereof, and a positive stop for arresting the cup in the discharge position and effective to cause a discharge of the granular substance in the form of a spray over the popcorn on the platform. 40

4. In popcorn dispensing apparatus, means for popping raw corn including a container for the corn, means effective upon completion of the popping operation to move the container to a position wherein the popcorn is discharged from the container onto a platform, means for returning the container to its initial position, means operable in timed relation to returning the container to its initial position for distributing salt over the popcorn on the platform, and power driven cam means effective to control the operation of each of the aforesaid means in predetermined timed relationship. 50

5. In popcorn dispensing apparatus, means for popping raw corn including a container adapted to receive the corn and supported for swinging movement to a position wherein the popcorn is discharged from the container onto a platform, means for swinging the container to the discharge position thereof, means for returning the container to its initial position, a salter, and power driven cam means operating in timed relation to movement of the container to its initial position. 70

- tion to actuate said salter and distribute a quantity of salt over the popcorn on the platform.
6. In popcorn dispensing apparatus, a receptacle adapted to contain a granular substance and having a discharge opening in one side wall through which the substance is adapted to flow, a plate normally closing the discharge opening and supported for swinging movement in a direction to open said opening, a cup movable by the plate and adapted to assume a position in registration with the discharge opening when said plate is swung to a position wherein the discharge opening is open, means for moving said plate to its closed position in timed relation to filling of the cup with the granular substance, and means for positively stopping movement of the plate to the last named position and effective to cause the discharge of the granular substance from the cup in the form of a spray.
- 20 7. In popcorn dispensing apparatus, a receptacle adapted to contain a granular substance and having a discharge opening in one wall through which the substance is adapted to flow, a plate normally closing the discharge opening and supported for swinging movement to a position wherein the discharge opening is open, a cup supported on said plate in a position predetermined to register with the discharge opening when the latter is opened by the plate, means for moving the plate at a relatively fast rate to its closed position, and means for abruptly interrupting said movement and thereby causing the granular substance in the cup to be discharged from the cup in the form of a spray.
- 30 8. In popcorn dispensing apparatus, a cup adapted to receive a supply of a granular substance and supported for swinging movement from a discharge position to an upright position, means for actuating the cup including a reciprocable bar operatively connected to the cup, a cam engageable with the bar to move the latter in a direction to swing the cup to its upright position and then releasable from the bar, and a spring effective when the cam releases the bar to move the bar in the opposite direction at a relatively fast rate and to swing the cup to its discharge position, and a positive stop arresting swinging movement of the cup to its discharge position in a manner to effect discharge of the granular substance from the cup in the form of a spray.
- 50 9. In popcorn dispensing apparatus, means for popping raw corn including a container adapted to receive the corn, a rockshaft operatively connected to the container for swinging the latter to a position wherein the popcorn is discharged from the container on a platform, a cup adapted to contain a supply of a granular substance and supported for swinging movement from a discharge position to an upright position, means for discharging the granular substance into the cup when the latter is in its upright position, means for actuating the cup including a reciprocable bar operatively connected to the cup, means on said rockshaft effective to move the bar in a direction to move the cup to its upright position when the container is returned by the shaft to its initial position and to release the bar during the final movement of the container to its initial position, a spring effective to move the bar in the opposite direction at a relatively fast rate to swing the cup to its discharge position, and a positive stop abruptly arresting movement of the cup by the spring and effective to cause a discharge of the granular substance from the cup in the form of a spray over the popcorn on the platform.
10. In popcorn dispensing apparatus, a receptacle adapted to contain a granular substance and having a discharge opening in one side wall through which the substance is adapted to flow, a valve plate normally closing the discharge opening and supported for swinging movement to a position wherein the discharge opening is open, a cup secured to the valve plate in a manner to assume an upright position in registration with the discharge opening when the valve plate is swung to a position wherein said opening is open, means for actuating the valve plate including a reciprocable bar operatively connected to the valve plate, means for moving the bar in a direction to swing the valve plate to a position wherein the cup registers with the discharge opening and to subsequently release the bar, a spring responsive to releasing of the bar by said means to move the latter at a relatively fast rate in a direction to swing the valve plate to a position wherein the discharge opening is closed thereby and to a position wherein the cup is tilted with respect to its upright position, and a positive stop abruptly arresting movement of the plate to its closed position and effective to cause a discharge of the granular substance from the cup in the form of a spray.
- 20 11. In popcorn dispensing apparatus, means for popping raw corn including a container adapted to receive the corn and movable from a popping position to a position wherein the corn is discharged onto a platform, a salter adapted to distribute salt over the popcorn on the platform, a power driven cam effective to move the popping container to the discharge position thereof, and means also actuated by said cam for operating the salter.
- 30 12. In popcorn dispensing apparatus, a ratchet wheel supported for rotative movement in opposite directions, means normally urging the ratchet wheel in one direction, a pawl engageable in a notch formed in the periphery of the wheel preventing rotation of the ratchet wheel by said means, coin controlled means effective to move the pawl out of engagement with the ratchet wheel and permit movement of the ratchet wheel by said first named means, means engageable with the ratchet wheel to limit rotative movement thereof in said first named direction, means for releasing the limiting means from the ratchet wheel to permit continued rotation of the wheel in said first mentioned direction, means responsive to releasing the ratchet wheel by said limiting means to stop further movement of the ratchet wheel in the first mentioned direction, and a switch located in an electric circuit and operated by said ratchet wheel.
- 40 13. In popcorn dispensing apparatus, a ratchet wheel revoluble in opposite directions, a pawl engaging in a notch in the periphery of the wheel preventing rotation of said wheel in one direction, a spring between the pawl and wheel normally urging the wheel in the above named direction, a coin controlled member effective upon movement in one direction to release the pawl and permit rotation of the wheel in the aforesaid direction, means engageable with the ratchet wheel to limit rotative movement in said direction and releasable from the wheel upon movement of the coin controlled member in the opposite direction to permit continued rotation of the ratchet wheel in said first named direction, means for limiting the extent of continued rotation of the wheel, a switch in an electric circuit operated by the wheel during said continued rotation to 50
- 50 55 60 65 70 75

close the electric circuit, and means operating in predetermined timed relation to closing of the switch to automatically rotate the wheel in the opposite direction to its initial position and open the switch.

14. In popcorn dispensing apparatus, a ratchet wheel revoluble in opposite directions, a pawl engageable in a notch in the periphery of the wheel to prevent rotation of said wheel in one direction, a spring connecting the wheel and pawl tending to rotate the wheel in the first named direction, a coin controlled member movable in one direction to disengage the pawl from the wheel and permit rotation of the wheel under the action of the spring in said first named direction, means engageable with the wheel to limit rotation thereof in said first named direction and releasable upon movement of the coin controlled member in the opposite direction to permit continued rotation of the ratchet wheel, means on the wheel engageable with the pawl to limit said continued rotation of the wheel, a switch arranged in an electric circuit and normally maintained open by the wheel, and means on said wheel effective during the continued rotation thereof to permit closing of the switch.

15. In popcorn dispensing apparatus, a ratchet wheel revoluble in opposite directions, a pawl engageable in a notch in the periphery of the wheel to prevent rotation of said wheel in one direction, a spring connecting the wheel and pawl tending to rotate the wheel in the first named direction, a coin controlled member movable in one direction to disengage the pawl from the wheel and permit rotation of the wheel under the action of the spring in said first named direction, means engageable with the wheel to limit rotation thereof in said first named direction and releasable upon movement of the coin controlled member in the opposite direction to permit continued rotation of the ratchet wheel, means on the wheel engageable with the pawl to limit said continued rotation of the wheel, a switch arranged in an electric circuit and normally maintained open by the wheel, and means on said wheel effective during the continued rotation thereof to permit closing of the switch.

16. In popcorn dispensing apparatus, means for

popping raw corn including a container adapted to receive the raw corn and movable in opposite directions to agitate the corn, means for moving the container to a position wherein the corn is discharged from the container, a platform located to receive the popcorn discharged from the container, means associated with the platform to separate any raw kernels from the popcorn, and means for tilting the platform to discharge the popcorn.

17. In popcorn dispensing apparatus, a receptacle adapted to contain a granular substance and having a discharge opening in one wall through which the substance is adapted to flow, means normally closing the discharge opening and movable to a position wherein said opening is open, and a cup responsive to movement of said means to open the discharge opening to collect the granular substance flowing from the opening and operable upon movement of the means to close said opening to discharge the granular substance therefrom.

18. In popcorn dispensing apparatus, a receptacle adapted to contain a granular substance and having a discharge opening in one wall through which the substance is adapted to flow, means normally closing the discharge opening and movable to a position wherein said opening is open, a cup responsive to movement of said means to open the discharge opening to collect the granular substance flowing from the opening and operable upon movement of the means to close said opening to discharge the granular substance therefrom, means effecting movement of the cup to its discharge position at a relatively fast rate, and a positive stop interrupting movement of the cup to the last named position providing for discharging the substance therefrom in the form of a spray.

19. In popcorn dispensing apparatus, means for popping raw corn including a container adapted to receive a quantity of raw corn, means for moving the container to a position wherein the popped corn is discharged therefrom, a pivotally mounted cup adapted to contain a supply of granular substance, and means operating in timed relation to movement of the container to discharge the popped corn to swing the cup to a position wherein the contents thereof are distributed over the popped corn.

JAMES O. COLTMAN.
